UNITED STATES PATENT OFFICE.

VIRGINIA D. BURNAM, OF HUNTSVILLE, ALABAMA.

DESIGN FOR A COMBINED SEAT AND CABINET.

No. 38,978.

Specification for Design.

Patented Dec. 31, 1907.

Application filed October 14, 1907. Serial No. 397,459. Term of patent 14 years.

To all whom it may concern:

Be it known that I, VIRGINIA D. BURNAM, a citizen of the United States, residing at Huntsville, in the county of Madison and State of Alabama, have invented a new, original, and ornamental Design for a Combined Seat and Cabinet, of which the following is a specification, reference being had to the accompanying drawing, forming part thereof.

The figure is a perspective face view of the combined seat and cabinet embodying my new design.

I claim—

The ornamental design for a combined seat and cabinet, as shown.

VIRGINIA D. BURNAM.
